UNITED STATES PATENT OFFICE.

CLARA E. HALL, OF CINCINNATI, OHIO.

STRIP-GUIDE.

1,155,920.

Specification of Letters Patent.

Patented Oct. 5, 1915.

Application filed August 5, 1914. Serial No. 855,298.

To all whom it may concern:

Be it known that I, CLARA E. HALL, a citizen of the United States, residing at Cincinnati, in the county of Hamilton and State of Ohio, have invented new and useful Improvements in Strip-Guides, of which the following is a specification.

This invention relates to a guiding attachment to facilitate stirring operations on a sewing machine, the object in view being to provide a simple, convenient and accurate attachment which serves to guide the material to the needles of the machine and also fold the material to be stirred, the attachment enabling material to be stirred independently of the foundation work or stirred and simultaneously stitched to the foundation.

A further object of the invention is to provide means for adjusting the guides to suit material of different widths; also means for separably attaching interchangeable folders of different sizes to the body of the attachment.

With the above and other objects in view, the invention consists in the novel construction, combination and arrangement of parts, as herein described, illustrated and claimed.

In the accompanying drawings, Figure 1 is a perspective view of the attachment complete. Fig. 2 is a vertical longitudinal section through the same. Fig. 3 is a vertical cross section taken adjacent to the folder tongue. Fig. 4 is a detail view of one of several interchangeable folders of different widths. Fig. 5 is a fragmentary view showing the product of the machine and the guiding attachment.

The attachment of this invention is adapted to be used in combination with a stirring machine and is in the nature of a combined guide and folder used as an auxiliary to the stirring machine.

The device comprises in its essential construction, a base plate 1 which is held at a slight elevation above the table of the stirring machine, the end portions of the base plate being offset as shown at 2 and extended to form attaching flanges 3 adapted to be secured or otherwise fastened to the machine table.

A pair of work directing guides 4 are mounted so as to be capable of being slid longitudinally of the elevated portion of the base plate, each of said guides comprising a retaining portion or flange 5 which bears

against the upper surface of the bed plate 1, a downwardly extending edge gage portion 6 which extends below the bed plate, and an inwardly extending work supporting apron 7. The aprons 7 may be made of suitable width so that they may overlap each other when the guides are brought close to the folder to be described.

The bed plate 1 is provided along the front and rear edges thereof with holes 8 which are adapted to receive shiftable stop pins 9 which engage the guides 4 and limit the extent to which they move apart, said pins therefore serving to position the guides in accordance with the width of the work.

11 designates the folder which extends transversely of the base plate 1 and in parallel relation to the guides 4, said folder being arranged on the upper surface of the bed plate and being held in a certain fixed relation thereto by means of a tongue 12 which is adapted to be inserted under retaining loops 13 struck up from the elevated base plate 1. This enables a series of interchangeable folders of different widths to be attached to the bed plate 1 to accommodate corresponding widths of material to be stirred. Each of the folders 11 is provided on its upper side with inwardly extending guide flanges 15 under which the material to be stirred is confined and guided.

16 represents a central upstanding guiding rib for centering the trimming in relation to the foundation material.

From the foregoing description, taken in connection with the accompanying drawings, it will now be understood that the guiding attachment may be applied to any stirring machine table and fastened thereto. The guides 4 may be adjusted toward and away from the folder 11 in accordance with the width of the work and by providing a plurality of interchangeable folders, material of different widths for the stirring operation may be employed. Very attractive and neat trimming may thus be produced and the foundation material and the trimming may be guided and stitched together in a single passage of said material and trimming through the stirring machine. The attachment will be found particularly useful in fancy dress making establishments and coffin factories.

In the use of the attachment hereinabove described, the foundation goods are inserted in the guides 6, said foundation material

passing under the plate 1 and resting upon the flanges or aprons 7. The trimming which is, of course, much narrower is inserted and caused to travel through the folder and guide 11, the edges of the trimming strip being turned downwardly under the central portion of the strip so as to touch the central upstanding rib 16 which serves to center the edges of the trimming strip relative to the body thereof. The folded trimming strip thus passes over the plate 1 and is laid upon the foundation goods passing under said plate, both the foundation and the trimming then passing to the needles of the stirring machine which performs the stirring action, the strip guide of this invention serving merely to guide the material to the needles of the stirring machine.

What I claim is:—

1. A guiding attachment for stirring machines, comprising an elevated base plate, a folder attached to the upper side of said bed plate and detachable therefrom, flanged work guides adjustable toward and away

from said folder and each other mounted 25 on said plate and each provided with a work supporting apron which lies beneath the bed plate, said folder embodying U-shaped flanges in spaced relation to each other, and an upstanding centering rib between said 30 flanges.

2. A guiding attachment for stirring machines, comprising an elevated base plate, flanged work guides adjustable on said plate transversely to the path of movement of the 35 work, and a folder secured to the upper side of said bed plate and provided with a tongue parallel to the lower face thereof and adapted to engage the bed plate and detachably fasten the folder in place on the 40 bed plate.

In testimony whereof I affix my signature in presence of two witnesses.

Miss CLARA E. HALL.
